MECHANISM FOR PRECISION SWITCHES

Edwin August Miller, Fairfield, Conn.

Application April 3, 1946, Serial No. 659,197

3 Claims. (Cl. 200—67)

1

This invention relates to mechanism for precision switches, including switches adapted for alternate electric currents.

The objects of the invention are to provide a snap action switch which maintains a constant maximum contact pressure up to the breaking point; to provide a switch having actuating means including a flat spring to which resilient properties are imparted while a portion of the spring is held in a predetermined manner; and to provide a switch the mechanism of which is compact, with the least required exertive pressure of operation, and adapted for a reduced arc of oscillation.

Referring to the accompanying drawing, the Figure 1 is an erect elevation of the device, illustrating the insulation casing in cross-section and the mechanism in a maintained at-rest position; Figure 2 is a similar elevation but illustrating the mechanism in an operated position; Figure 3 is a top surface view of the oscillating member fixedly supported at one end to the casing, the casing illustrated in outline; Figures 4 and 5 are diagrammatic layouts of different mechanical positions of the oscillating member and associated parts; and Figure 6 is a detail illustrated in perspective.

With more particular reference to the accompanying drawing, in which there is illustrated one form only of the invention with regard to the novel mechanism and manner by which the improvement herein set forth is accomplished. Other forms within the scope of the invention may be obvious.

The invention herein set forth is an improvement of mechanism disclosed and claimed in a previous application for patent, Serial Number 583,049 filed by me on March 16, 1945, now Patent No. 2,428,172, issued Sept. 30, 1947, and in which an opening of an oscillating member contains a tongue, and its connection with a leaf spring through the medium of a rigid link, of greater length than that of the opening. The improvement, about to be herein set forth, eliminates the rigid link.

The casing 1, of insulation material, illustrated in cross-section, accessibly provides wire connection terminals 2, 3 and 4, adapted for electric wiring (not illustrated) for the establishment of separate alternate circuits within which the switch may be inserted. The inner extremities of terminals 2 and 3 provide surfaces for use as spacedly aligned fixed contacts 5 and 6 supported by the casing 1. The sheet-metal oscillating body member 7, one end of which is anchored, as at 8, within the casing 1 where it is provided with a

2

permanent connection with the inner end of the terminal 4, as illustrated by the Figures 1 and 2, carries at its opposite end the upper and lower superposed contact surfaces 9 and 10, respectively, adapted for alternate engagements with the fixed contacts 5 and 6 in maintained at rest and operated positions of the oscillating body member 7. The tongue 11 is illustrated as integral with the body member 7 and pendulously formed by being cut on three sides from within the central surface-length thereof although, if desired, the tongue 11 may be a separate piece of sheet-metal set within the opening 7A of the body member 7 having the fourth side cut out, the separate piece being fixed to the body member 7. A thin leaf spring 12 is secured at its upper end to the insulation casing 1 and the free lower end is movably held within the slot 13 of the casing 1. Said leaf spring 12 is provided at its side edges with the open recesses 14 within which to fit the extended lugs 15 of the tongue extremity as a means of hinged assembly. The tension of the leaf spring 12 is exerted outwardly against the tongue 11 in one direction only to maintain the tongue normally buckled up in an over-centering position relative to the body 7 of the oscillating member.

As illustrated by the Figure 1, the oscillating body member 7 and connected parts of the precision switch mechanism are held at rest in said over-centering position. In the Figure 2, the mechanized parts are illustrated as having been operated by means of manual pressure of the thumb 16 placed upon the push element 17 whereby the tongue 11 is depressed below the oscillating body member 7, to an undercentering position.

Due to the over-all length of the combined tongue 11 and leaf spring 12, being slightly greater in length than the opening 7A of the oscillating member 7 in which opening 7A they operate, the tongue 11 is forced to buckle with regard to the oscillating body member 7. In the forced movement by means of pressure of the thumb, or similar means, upon the push element, the over-centered tongue is compelled to leave such over-centering position, passing through a center to an under-centering whereby the body member is sufficiently distorted so that the transition is one of sudden snap action wherein the free end of the oscillating body member 7, carrying the superposed contacts 9 and 10, engages its contact 9 with the fixed contact 5 supported by the casing 1, which contact engagement is maintained as long as manual pressure remains upon the push element 17, as illustrated by the Figure 2. With

the release of such pressure the tongue 11 passes back through center to its normal over-centered position, again returning the engagement of the contact 10 with the fixed contact 8 supported by the casing 1, as illustrated by the Figure 1.

While manual pressure is herein illustrated as means by which the precision switch is operated to one of its extreme positions, it is to be understood that such movement of operation is adapted to be accomplished by any other means, such as when the invention is applied as a part of an automatic means adapted for precision control in mass production of an article, in which case the switch may be mechanically operated as a part of such means.

In the Figures 4 and 5, it will be noted that the full line 1 designates the body of the oscillating member, and the dotted line 11 represents the tongue member. In the Figure 5 the tongue 11 is shown overcentered with relation to the body 1, while, in the Figure 5 the tongue 11 is shown as under-centered. Such positions of the tongue 11 determine engagements of the contacts 9 and 10 carried by the body member 1 relative to the fixed contacts 8 and 6.

It will be noted further that, in the Figures 1 and 4, the tongue 11 is permanently bent upwardly, at 11A, to normally maintain the tongue's upwardly buckled position engaged with the extremity 17A of the unoperated push element 17, and the contact 9 of the distorted body member 1 normally engaged with the fixed contact 8. In the Figures 2 and 5, the tongue 11 is shown in operated position with the tongue 11 downwardly buckled and engaged between the extremity 17A of the manually maintained push element 17 and the extremity of the fixed stop 18, and the contact 10 of the distorted body member 1 engaged with the fixed contact 6. However, as soon as the manual pressure is removed from the push element 17, the tongue 11 and the distorted body member 1 snaps back to their normal positions, as illustrated by the Figures 1 and 4.

It is to be understood that, while the tongue 11 is herein illustrated as positioned within the central opening 1A of the body member 1, the tongue 11 may just as well be positioned marginally with regard to a body member.

I claim:

1. A snap-acting control mechanism for a precision switch, the mechanism comprising a sheet-metal oscillating member of which one end is fixed to a base and the opposite end is movable along an arc between two fixed stops, said member having an elongated opening therethrough; a resilient tongue positioned within said opening and fixed at one end to said oscillating member; an actuator movably mounted upon said base for movement along a direct plane intersecting the plane of the oscillating member and having an extremity resting down upon an intermediate portion of said tongue; an arcuate-shaped spring member both ends of which engage a base sup-

port upon a surface plane which is parallel to said intersecting plane, the arcuate portion of said spring member hingedly engaging the free extremity of said tongue in such manner that the spring member's compressive force maintains said tongue under compression to maintain the intermediate portion of said tongue bowed either above or below said oscillating member thereby determining the position of the contacts, carried by said oscillating member in a snap-acting movement, with respect to either of said fixed stops.

2. A snap-acting control mechanism for a precision switch, the mechanism comprising an oscillating member of which one end is fixed to a base and the opposite end is movable along an arc between two fixed stops, said member having an elongated opening therethrough; a resilient tongue positioned within said opening and having one end fixed to oscillating member; an actuator movably mounted upon said base for movement along a direct plane intersecting the plane of the oscillating member and having an extremity resting down upon an intermediate portion of said tongue; a spring supported by said base and having a hinged connection with the free end of said tongue in such manner that the spring's compressive force maintains said tongue under compression maintaining the intermediate portion of said tongue bowed either above or below said oscillating member thereby determining the position of the contacts, carried by the oscillating member in a snap-acting movement, with respect to either of the fixed stops.

3. An oscillating member of a snap-acting control mechanism for a precision switch, said member comprising a flexible body of which one end is supported by a base and the other end being provided with contact surfaces; a tongue secured at one end to said body member; a spring supported by said base remote from said contact surfaces and having a hinged connection with the free end of said tongue, said spring exerting a compressive force along the plane of the oscillating member against the extremity of said tongue, and the overall length of the connected tongue and spring being greater than the space between the place of securement of said tongue to said body member and the supporting base of said spring; and an actuator movably mounted upon said base for movement along a direct plane intersecting the plane of the oscillating member and having an extremity resting upon the intermediate portion of said tongue.
